GOLF CART

Robert Maltarp, Barrie, Ontario, Canada, assignor to Rulendo Manufacturing & Eqpt. Ltd., Barrie, Ontario,
Canada

Continuation-in-part of design application Ser. No. 12,806,
July 7, 1968. This application Aug. 11, 1969, Ser.
No. 18,616

Term of patent 14 years

Int. Cl. D12—02

U.S. Cl. D14—3

FIG. 1

FIG. 2

FIG. 1 is a perspective view of a golf cart showing my new design, and

FIG. 2 is a front view of the golf cart.

The golf bag and clubs shown in broken lines are included for illustrative purposes only.

The side of the golf cart not shown in FIG. 1 has the same appearance as the side shown therein.

This application is a continuation-in-part of my copending application Ser. No. D. 12,806, filed July 7, 1968, now abandoned.

I claim:

The ornamental design for a golf cart, as shown and described.
